UNITED STATES PATENT OFFICE.

FREDERIK VAN GELDEREN, OF CHICAGO, ILLINOIS.

DESIGN FOR A LAMP-BODY.

44,459.

Specification for Design.

Patented Aug. 5, 1913.

Application filed April 16, 1913. Serial No. 761,609. Term of patent 14 years.

To all whom it may concern:

Be it known that I, FREDERIK VAN GELDEREN, residing at Chicago, in the county of Cook and State of Illinois, have invented a new, original, and ornamental Design for Lamp-Bodies, of which the following is a specification, reference being had to the accompanying drawing, forming part hereof.

The drawing shows a perspective view of said design, which comprises an approximately frusto-conical body 1 whose lower or enlarged end is encircled by an upwardly flaring wall 2, below which is disposed a

downwardly flaring skirt or flange 3, the members 2 and 3 being separated by a cylindrical wall 4 of restricted diameter. Depending below the lower edge of the member 3 is a frusto-conical member 5 of smaller diameter than the member 3.

I claim:

The ornamental design for a lamp-body, as shown and described.

FREDERIK VAN GELDEREN.
